COIN-WRAPPING DEVICE AND MEANS

William G. Newby, Sr., Hertford, N. C.

Application June 15, 1948, Serial No. 33,100

1 Claim. (Cl. 93—2)

1

This invention relates to means for wrapping coins, and particularly to means for wrapping a predetermined invariable number of coins to form standard coin packages.

The main object of my invention is to make it readily possible to wrap a certain number of coins without the necessity of counting the coins to be wrapped.

Another object is to provide means for facilitating wrapping predetermined groups of coins conveniently and speedily in order to save time and be in a position to handle large quantities of coins.

A further object is to have means of the indicated character made at low cost and of simple form to facilitate manufacture, distribution and use thereof.

It is also an object to provide means for the indicated purpose which includes not only means for gauging and supporting the coins to be wrapped, but also a special cooperating means for wrapping each number of coins thus gauged and supported.

Other objects and advantages of my invention will appear in further detail as the specification proceeds.

In order to facilitate ready comprehension of the invention and its salient features, this invention is illustrated on the accompanying drawing forming a part hereof, and in which:

Figure 1 is a perspective view of a coin-wrapping device made according to the invention and embodying the salient features thereof in a practical form, a coin-wrapper blank being shown in broken lines in position upon the device;

Figure 2 is a longitudinal section of the device of Figure 1, as taken on line 2—2;

Figure 3 is a transverse section of the same device taken on line 3—3 in Figure 1;

Figure 4 is a perspective view of a coin wrapper fitting the device of Figure 1 and shown in the latter figure in broken lines, as already indicated;

Figure 5 is a fragmentary section taken on line 5—5 in Figure 1.

In the various views the same reference numerals indicate the same or like parts throughout.

In various establishments where large numbers of coins are handled, it is self-evident that to manually count such coins and pack them into standard packages for depositing in a bank is a tedious chore which is burdensome and wasteful of time if some expedients are not adopted to speed up the work of handling the coins. In larger establishments, it is, of course, well known

2

that counting machines are used, but in many instances the cost of the latter is not justified so that many clerks are occupied in manually counting the coins as though there were no devices whatever for facilitating such duties, and this is especially true in smaller establishments.

After considering this problem carefully, I have found it possible to design simple means for facilitating and speeding up the counting of coins and wrapping the same in standard packages, as will now be set forth in detail.

In the practice of my invention, and referring again to the accompanying drawing, a coin-wrapping device, generally indicated at 6, primarily includes a gauging board 7 having substantially parallel side edges 8, 9, with the far end 10 substantially square with sides 8 and 9, while the near end 11 is cut obliquely for a purpose which will shortly be explained. A short distance from the far end 10 a limited transverse groove 12 is cut in the gauging board 7 terminating sharply at both sides in the end walls 13 and 14, the curvature of the groove being such that it will fit the edge of a coin standing upright in said groove with the sides of the coin parallel to the sides 8 and 9 of the board. The length of this groove is accurately cut to receive an exact number of coins intended to form a standard package, say for example, fifty or a hundred pennies, twenty nickels or ten or twenty dimes, twenty quarters, and so forth. In other words, if the groove is filled from wall 13 to wall 14 with the proper type of coin for which the groove is designed, a given number of coins will be accommodated and no more, with the assurance that the count is accurate and the coin package afterwards wrapped will contain a standard number of coins, and therefore be a standard coin package for the type of coin wrapped.

It is evident that if a wrapper or paper or the like 15 is laid upon the board and substantially conforms to the outline thereof, it will be a proper form to enclose the coins and constitute the exact size and shape of wrapper required for the package. In order to facilitate placing the wrapper in proper position on the board, a pair of side edge guides 16, 17 are secured to the edges 8 and 9 of gauging board 7 by means of screws or nails 18, the upper ends of the guides 16 and 17 being bent inwardly toward each other in the form of a pair of lugs 19 and 20, beneath which the wrapper 15 may be slid into position for the wrapping operation.

On the other hand, in order further to cooperate with the gauging board 7 in accurately gaug-

ing and then wrapping the coins, the wrapper 15 has a pair of cut-out side portions 21 and 22 forming a neck portion 23 and 23 of the same width as the length of groove 12 from wall 13 to wall 14, and virtually dividing the wrapper 15 into two sections, namely a short initial wrapper 24 and a longer finishing wrapper 25 terminating in the oblique end 26 forming the closure of the wrapper which may be provided with adhesive, as at 27, if desired.

The arrangement is such that when a wrapper 15 is slipped into position upon the gauging board 7 between the guides 16 and 17, and, of course, beneath the lugs 19 and 20 thereof and with the neck portion 23, 23 substantially registering with the upper edges of end walls 13 and 14 of groove 12, a group of coins may be packed into the groove, as indicated at 28. The immediate result is that the neck portion 23 is weighted by the coins and brought down into the groove, as may readily be seen in Figures 2 and 3, when the initial wrapping portion 24 may be used at first to begin the wrapping of the coins, after which they may be rolled with the side flaps 29 and 30 folded in upon the coins at the end thereof and the coins thus initially wrapped rolled up on the longer wrapper portion 25 and the adhesive portion 27 pasted on the end to finally close the wrapper. Of course, many wrappers are known that use no adhesive, and the latter may therefore be omitted if desired. It is to be noted, however, that due to the formation of the wrapper including the cut-out portions 21 and 22 which leaves the narrow neck 23, 23 exactly registering with the length of the groove 12, the initial step of wrapping is greatly facilitated by allowing the coins 28 to press down the neck 23 into the groove and thereby automatically start the wrapping. The coin wrapper thus cooperates with the gauging board to produce the final result of turning out quickly wrapped coin packages or rolls. It is to be noted that for each type of coin to be wrapped, the gauging board 7 is made to order for that coin, with the coin slot of precisely the length to receive a stipulated number of this type of coins and no others. For example, the slot is made to receive exactly fifty or one hundred pennies, and, naturally, the wrapper is likewise made of the proper size accordingly. The same principles apply to nickels, dimes and quarters, etc., the board in each case being accurately made to accommodate the coin specified by the one ordering it, and the wrappers being similarly made of the corresponding size.

In fact, each gauging board may be particularly marked and identified to point out the type or denomination of coins for which it is made. This feature may even hold in identifying boards to distinguish a board adapted for receiving forty Jefferson nickels to make up \$2.00 from one that serves to receive forty Buffalo nickels, as the groove length which accommodates forty Jefferson nickels is actually long enough to receive forty-two Buffalo nickels, the latter being slightly thinner than the Jefferson nickels.

The gauging board 7 may be made of wood, plastic or metal, while the guides 16 and 17 with their upper retaining lugs 19 and 20 are preferably of metal or the like, and, of course, the wrapper 15 is conventionally of paper or similar material.

Manifestly, variations may be resorted to and features may be modified or used without others within the scope of the appended claim.

Having now fully described my invention, I claim:

A coin-wrapping device comprising a substantially rectangular flat plate which is elongated, the plate being provided in its top face and near and inwardly of one end of the plate with a transverse elongated cylindrically curved groove for receiving a stack of coins, the opposite ends of the groove terminating near and inwardly of the opposite side longitudinal edges of the plate and forming shoulders which are flush with the top of the plate, a pair of laterally oppositely disposed substantially L-shaped guides secured to the opposite sides of the plate near and inwardly of the end of the plate remote from the transverse groove, the tops of the guides projecting laterally inwardly over the top of the plate and being spaced slightly from such top, and a substantially rectangular wrapper of thin sheet material mounted upon the top of the plate and engaging beneath the L-shaped guides and having its marginal edge arranged substantially flush with the marginal edge of the plate, the wrapper being provided in its longitudinal side edges with a pair of laterally oppositely disposed substantially rectangular notches, the notches being disposed adjacent to the shoulders at the opposite ends of the groove and exposing substantially the entire top surfaces of the shoulders, the inner ends of the notches being arranged substantially flush and in alignment with the opposite ends of the groove, the notches forming a narrowed neck portion extending across the top of the groove and long and short wrapper portions arranged upon opposite sides of the groove, whereby a stack of coins can be placed upon the neck portion which will sag into the groove between the shoulders so that the short wrapper portion may be folded over the stack of coins to initially wrap them, the initially wrapped stack of coins then being rolled over the long wrapper portion to complete the wrapping of the stack.
